UNITED STATES PATENT OFFICE.

OWEN C. WATKINS, OF FESTUS, MISSOURI.

WEATHER STRIP.

Application filed March 15, 1926. Serial No. 94,880.

The invention relates to improvements in weather strips designed for use upon inwardly swinging casement windows, and the object of the invention is to provide a new and improved construction and arrangement of parts which will be exceptionally simple and inexpensive, yet will be highly efficient and desirable, provision being made whereby a movable strip is swung downwardly to operative position when the sash is closed and is swung upwardly to a released position when said sash is opened.

With the foregoing in view, the invention resides in the novel subject matter herein-after described and claimed, the description being supplemented by the accompanying drawing.

Figure 1 is a perspective view of a casement window equipped with my invention. Figures 2 and 3 are vertical sectional views, partly in elevation, showing the manner of operation of the movable strip.

Figure 4 is an additional sectional view cut in a different plane from Figures 2 and 3 and showing the spring which constantly exerts a lifting force on the movable strip, so as to raise it to inoperative position as soon as permitted to function in this manner.

Figure 5 is a perspective view of the device disconnected from the sash.

In the drawing above briefly described, 6 designates the sill of a casement window and the numeral 7 designates two inwardly swinging sashes. A bead 8, preferably formed from a single metal plate, as shown, is secured upon the sill 6 and extends throughout the length thereof, and the lower edge of each sash 7 is provided with a longitudinal recess 9 which extends throughout the length of said edge and opens to the outer side of the sash, but not through the inner side thereof, the sash being formed with a groove 10 in the angle between the upper and inner walls of the recess 9.

A movable weather strip 11 is provided to outwardly decline over the bead 8 as shown in Figures 3 and 4, when the sash is closed. The strip is formed from a single elongated piece of sheet metal having one edge rolled to provide a tubular bead 12, said bead having relatively small notches 13 near its ends and a larger notch 14 between its ends. Bearings 15, preferably formed by bending metal strips at one end, are positioned in the notches 13, while a coiled torsion spring 16 is disposed in the notch 14. A rod 17 passes

entirely through the tubular bead 12 and the notches 13 and 14, said rod passing through the bearings 15 and through the spring 16. An eye 18 at the angle of a bell crank 19, is positioned on one end of the rod 17 and is received in a notch 20 in one extremity of the tubular bead 12, one arm 21 of said bell crank being secured to the strip 11, while the other arm 22, is adapted for co-action with the bead 8 to swing said strip 11 downwardly against the action of the spring 16, when the sash is closed.

When mounting the device in the recess 9, the metal strips 23 from which the bearings 15 are bent, are secured by suitable fasteners 24 to the inner wall of said recess 9, the tubular bead 12 and the parts located in its notches, then extending into the groove 10, so that the portion of the sash at the other side of this groove, forms a water shed, preventing any water from entering above the strip 11. When the device is so applied, one end 25 of the spring 16 bears against the lower side of the strip 11 and the other end 26 of said spring, engages the inner wall of the recess 9. Thus, the spring has a constant tendency to raise the weather strip 11 to the horizontal position shown in Figure 2, in which position it will clear the bead 8. When the strip is positioned in this manner, the arm 22 projects downwardly so as to strike the bead 8 when the sash is closed, thereby swinging the bell crank 19 and moving the strip 11 downwardly to the outwardly declined position shown in Figures 3 and 4, in which position it will effectively prevent entrance of water, snow, sleet, wind, etc. As soon as the sash is opened, the pressure of the bead 8 against the arm 22 is relieved, allowing the spring 16 to swing the strip 11 upwardly, so that the sash may be easily opened.

Attention is invited to the fact that the bead 8 constitutes a stationary weather stop which will exclude any water which might by any possibility find its way beneath the movable stop 11. Moreover, this bead forms an abutment for co-operation with the arm 22, for the purpose of normally retaining the stop 11 in its outwardly declined position over the bead 8, and for causing such movement of said arm as to again swing the stop 11 downwardly, as the sash is closed. As the sash is swung open, the arm 22 leaves the bead 8 and permits the spring means 16 to come into play for the purpose

of raising the movable weather stop 11, clear of the bead 8. Attention is also invited to the fact that while the weather stop 11 and associated parts are preferably mounted in a recess such as 9, constituting a water shed, a shed of any other adequate form could be provided.

The invention is exceptionally simple and inexpensive yet will be efficient and in every way desirable. The results have been excellent from the details disclosed and they are therefore preferably followed, but within the scope of the invention as claimed, variations may be made.

15 I claim:

1. A weather seal adapted for mounting on a casement window sash for coaction with an upstanding sill carried bead extending throughout the length of the sill and projecting above the sill to form a water stop, said seal comprising an elongated metal strip having a tubular bead along one of its longitudinal edges, said bead being formed near its ends with notches, having another notch at one of its ends, and being formed with an additional notch between its ends, bearings in the notches near the ends of said bead having attaching means for anchorage to the sash, a coiled torsion spring in the notch between the ends of the bead, one end of said spring engaging the strip while the other end thereof is adapted to engage the sash, a rod passing loosely through the entire length of said tubular bead and spanning all of its notches, said rod passing through said bearings and said spring, and a bell crank having an eye received in the notch at the end of said tubular bead, said eye being mounted on one extremity of said rod, one arm of said bell crank being secured to said strip while the other arm thereof is adapted to coaction with the sill-carried bead to offset lowering of the strip against the action of the aforesaid spring.
- 45 2. A weather seal for a casement window sash, said sash having in its lower edge a longitudinal recess extending throughout the length of said edge and opening to the outer side of the sash and having a longitudinal groove in the angle between the upper and inner walls of the recess, said walls and groove forming a water shed, said seal com-

prising an elongated sill-carried bead formed from a single strip of metal bent longitudinally upon itself to form an upstanding portion and having its opposite edge bent laterally to form flanges for attachment to the sill, an elongated sealing strip having a tubular bead along its upper longitudinal edge, said bead having a plurality of notches, a rod passing through said bead, bearing members arranged in certain of said notches and engaging said rod the ends of said bearing members being secured to the inner wall of said recess, for hingedly supporting said sealing strip, a coiled torsion spring engaged with said rod in another of said notches, one end of said spring engaging said sealing strip while the other end engages the inner wall of said recess and a bell crank lever having an eye engaged with one end of said rod, one arm of said lever being secured to said strip while the other arm thereof is adapted for co-action with the sill carried bead to effect the lowering of the sealing strip when the sash is closed.

3. An inwardly opening casement window sash having a water shed throughout the width of its lower end, a weather stop extending longitudinally under said water shed and pivoted to the sash for movement from an outwardly declined normal position to a raised inoperative position, a stationary weather stop bead extending longitudinally of the window sill, said bead being normally disposed under the upper portion of said weather stop, spring means acting on said weather stop and tending to raise it clear of the bead, and an arm connected with said weather stop and normally abutting the inner side of said bead to retain said weather stop in its normal position against the action of said spring means, said arm moving away from said bead and permitting raising of said weather stop by said spring means as the sash is opened, said arm upon closing of the sash coming again into contact with the bead to again swing the weather stop downwardly to operative position.

In testimony whereof I have hereunto affixed my signature.

OWEN C. WATKINS.
